UNITED STATES PATENT OFFICE.

ERNEST H. SWIFT, OF HARTFORD, CONNECTICUT.

PACKAGE-ROLL OF METALLIC LEAF.

1,190,340.

Specification of Letters Patent.

Patented July 11, 1916.

Application filed February 25, 1914. Serial No. 821,024.

To all whom it may concern:

Be it known that I, ERNEST H. SWIFT, a citizen of the United States, residing at Hartford, in the county of Hartford, State 5 of Connecticut, have invented a new and Improved Package-Roll of Metallic Leaf, of which the following is a specification.

My invention relates to packages of metallic leaf that are wound upon a core, the 10 metallic leaf being placed upon a backing or base of paper or similar material before the winding takes place, and an object of my invention, among others, is to provide for such a roll a core that may be separated 15 by the use of an instrument that will not waste or cut away any of the material.

One form of package roll embodying my invention and in the construction and use of which the objects herein set out, as well 20 as others, may be attained, is illustrated in the accompanying drawings, in which—

Figure 1 is a view in side elevation of a package roll wound upon my improved core. Fig. 2 is an end view of the same. Fig. 3 25 is a detail side view of a separated disk. Fig. 4 is a view partially in lengthwise section through the core showing its action under the influence of the cutting tool.

By the use of my invention described 30 herein I am enabled to produce a package roll of metallic leaf having a core formed of extreme rigidity and strength, which is a desirable feature of wooden cores heretofore used, but which wooden cores were ob- 35 jectionable from the fact that they could not be cut without a waste of the material upon them. My improved package, how- 40 ever, possesses the advantage that the core may be cut without a waste of material and in a manner to produce a package having an extremely finished appearance.

In the accompanying drawings the num- 45 eral 5 indicates the core of my improved package roll, this core being formed of a single piece of paper spirally wound, the paper being of proper width to produce a package 7 of the required length, this core being wound upon a quill 6 of paper or similar material. The paper is tightly 50 wound to produce a core of the required thickness to possess the requisite qualities

as to rigidity, the several wraps or layers of the paper being free from any adherent material, and the end of the paper strip being secured in any desired manner. In fact 55 I contemplate cases where the end may not be secured.

The metallic leaf, with its base or back- 60 ing of paper or like material is wound upon this core to the desired extent, and a pack- 65 age is thus produced which may be easily separated into comparatively short lengths 8 by the use of a knife, the package being rotated in this operation and the knife cutting entirely through the metallic leaf and 65 the core, thus producing a package having extremely smooth sides. The formation of the core is such that it will not break and crack, as will a wooden core, if an attempt be made to cut it, but the several layers of 70 the paper of the core will slide one upon another to produce a gash of a width to permit ready entrance of the knife blade. That is, the superposed layers of paper in the core readily yield to the action of the knife 75 and permit it to easily enter the material and sever the short lengths from the main roll. The form that will be assumed by the core of the disk being severed is shown in Fig. 4 of the drawing. 80

While I have shown and described herein a satisfactory means of carrying my invention into effect, this may be changed to a greater or lesser extent without departing from the spirit and intent of the invention. 85

I claim—

1. A package roll of metallic leaf includ- 90 ing a core separately formed from paper tightly wound into a number of superposed layers to the required thickness, said layers being slidable one upon another.

2. A package roll of metallic leaf includ- 95 ing a core separately formed from paper of a width equal to the length of the core, said paper being tightly wound into a number of superposed layers to produce a core of the required thickness, said layers being slidable one upon another.

3. A package roll of metallic leaf includ- 100 ing a separately formed core composed of a single piece of paper wound into a number of superposed layers to produce the required

thickness for the core, said layers being
slidable one upon another.

4. A package roll of metallic leaf includ-
ing a core formed from a single piece of
5 paper spirally wound into a plural number
of superposed layers sufficient to produce
the required thickness for the core, and me-

tallic leaf with its backing wound upon said
core, said layers being slidable one upon an-
other.

ERNEST H. SWIFT.
